UNITED STATES PATENT OFFICE.

MAX R. URBAN, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed November 28, 1923. Serial No. 677,363.

To all whom it may concern:

Be it known that I, MAX R. URBAN, a citizen of the United States, residing in Elizabeth, in the county of Union and State of New Jersey, have invented certain new and useful Improvements in Typewriting Machines, of which the following is a specification.

This invention relates to typewriting machines, and more particularly to work-web-supplying and carbon-carrying means therefor. More particularly, it relates to typewriting machines of the continuous billing class.

15 In the continuous billing machine, as illustrated for example, in the patent to Wernery and Smith, No. 1,132,055, provision is ordinarily made of a long carriage-extension supported in part upon a rear extension of the machine frame, and having a track upon which a carbon-carrier is reciprocable toward and from the revoluble platen of the machine. The work-webs have heretofore been introduced into the machine 20 at the rear of the carriage-extension from stationary web-carrying rolls or other suitable web-supplying means located to the rear of the carriage-extension and generally at a substantial distance below it.

25 This arrangement of the web-supplying means is open to several objections. In order to make the web-supplying means accessible for the replenishment of the web and for other purposes, it was necessary that considerable space be provided at the back of the desk on which the machine was supported, and this was a drawback in crowded offices. The web-supplying means was not visible to the operator moreover, and hence one of the webs was apt to become exhausted without the operator's knowing about it. This would result in the writing of one less copy than intended until the fact that one of the webs had become exhausted was discovered, when it would be necessary, of course, to rewrite the form or forms of which an insufficient number of copies had been made. Then, too, a stretch of slack had to be provided in each web 40 between the stationary web-supplying means and the movable carriage-extension

to accommodate the relative movement of these parts, and these slack stretches of the webs, especially if separate narrow webs were employed, were apt to become disarranged, or tangled by the wind.

In accordance with the present invention, all of the above-mentioned difficulties are overcome by the provision of a web-supplying frame mounted for movement from side to side with the carriage. This frame is preferably mounted on the usual carriage-extension above the carbon-carrier. Web rolls may be mounted on the frame and are preferably arranged in a horizontal row, so that all are visible to the operator seated at the machine and are readily accessible for web replenishment. When the web upon one of the rolls is exhausted, the operator can observe the fact at once and can easily insert a fresh web-supply. The mounting of the web-supplying rolls to travel with the carriage eliminates the need for slack between the web rolls and the rear of the carriage-extension, and hence obviates the likelihood of the webs becoming disarranged by the wind, or by the twisting of the webs as the carriage travels from side to side. A substantial economy of office space may be effected also, due to the fact that the desk upon which the continuous billing machine is supported can be placed back to back with another desk, or can be placed against the wall.

The webs are directed by suitable guides from their supply rolls to the rear of the carriage-extension, and are thence led forward between the carbons of a carbon-carrier reciprocable toward and from the platen. The carbon-carrier may include the usual stepped frame, but the steps of the frame, according to one method of practicing the invention, are not used. Brackets are detachably connected to the carbon-carrier frame and bear carbon-carrying rolls, each of which rolls is provided with carbon for active use and also with a considerable reserve supply. Provision is made of means for holding the carbon-carrying rolls against rotation in the ordinary operation of the machine, but such means may be released when it is desired to replace a

wornout stretch of active carbons with a fresh stretch.

It is a feature of the invention that the supports for the work-web-supplying rolls are adjustable toward and from each other to accommodate different lengths of web-rolls between them, and are also adjustable together to locate the web in line with different selected fields of the platen. The carbon-roll-supporting brackets, too, are adjustable toward and from each other to accommodate carbon-rolls of different lengths in accordance with the width of the work-webs, and are adjustable together to locate the carbons in line with different selected fields of the platen, the adjustments of the carbon-roll-supporting brackets being made to correspond to the adjustment of the supports for the work-web-supplying rolls.

20 In accordance with one feature of the invention, the web-supply frame is detachably mounted upon the carriage-extension, and the carbon-roll-supporting brackets are detachably mounted on the carbon-carrier. The carbon-carrier frame has provision, as usual, for the attachment of carbon-holding blades. It will be seen, therefore, that the machine may be quickly converted for doing fan-fold work in the previously known manner.

25 The carbon-carrier may be converted for fan-fold work independently of the removal of the web-supply frame, and, conversely, the web-supply frame may be removed independently of the conversion of the carbon-carrier.

Provision is made for changing the work-web in the machine at will, when a different style or width is desired. The supports in which the ends of the web-supplying rolls are journaled are connected to each other to from a rigid truss, which is held to the remainder of the web-supply frame by its own weight and the weight of the rolls, and therefore may be removed at will from the frame. The carbon-carrier is also detachably mounted on the carbon-carrier base. When it is desired to substitute in the machine a web of a different width, or different in some other characteristic, from the web in the machine, the carbon-carrier and the web-supplying rolls may be removed from the machine together without disturbing the interleaved relation of the work-webs and carbons, and a truss bearing paper-webs of the desired width, together with a carbon-carrier having carbons of the desired width interleaved with said webs, may be substituted.

Other features and advantages will hereinafter appear.

In the accompanying drawings,

Figure 1 is a sectional side elevation on the line 1—1 of Figure 4, showing a continuous billing machine having the present invention applied thereto.

Figure 2 is a detail longitudinal vertical section on the line 2—2 of Figure 7, showing an end of the web-supporting truss, and its connection to an end member of the web-supply frame.

70 Figure 3 is a horizontal section on the line 3—3 of Figure 4, showing an end of the web-supporting truss.

Figure 4 is a transverse vertical section on the line 4—4 of Figure 1, looking toward the rear of the machine.

Figure 5 is a plan view, partly in section, of the carbon-carrier.

Figure 6 is a transverse vertical section through one of the web-rolls, as indicated by the line 6—6 of Figure 1.

Figure 7 is a plan view of the web-supporting truss.

In the continuous billing machine, keys (not shown) are depressed to swing types 55 10 upwardly and rearwardly to print against the front of a revoluble platen 11, journaled at its ends by a platen-axle 12 in a swing-frame 13 mounted on the traveling carriage 14 of the machine. The carriage 14 is movable from side to side in the usual manner upon a front rail (not shown) and a rear rail 15 supported by the machine frame 16. A rear carriage-extension 17, comprising brackets 18, transverse rods 19 and 20 and longitudinal rods 21, is mounted for movement with the carriage 14, being supported at the rear upon a rail 22 mounted at the rear of an extension 23 of the machine frame 16. The carriage-extension 17 has rails 24 upon which the base 25 of a carbon-carrier 26 is mounted for movement toward and from the platen 11. At line-spacing, the carbon-carrier 26 advances toward the platen with the work-webs A and carbons B. When the typing of a stretch of webs is completed, the swing-frame 13 is displaced to raise the platen 11 and thereby to permit straightening of the carbons B; the work-webs A are drawn forward to a gage 27; and the carbon-carrier 26 is thrust to the rear to withdraw the carbons from the completed section of web A. The platen 11 is then restored to normal position and the completed web-section is severed by means of a knife 28 located at the front of the platen. As thus far described, the machine is like the Wernery and Smith machine referred to above.

110 In accordance with the present invention, provision is made of a work-web-supply frame, which is mounted on the carriage-extension 17 for movement therewith from side to side of the machine. This frame consists principally of upright end members 29 and 30, mounted, respectively, at the front and rear of the carriage-extension 17 and a connecting roll-supporting truss 31. The end members 29 and 30 are in the form of inverted U's, the forward member 29 con-

sisting of vertical legs 32 and a horizontal body 33, and the rear member 30 consisting of vertical legs 34 and a horizontal body 35.

The lower ends of the legs of the end members 29 and 30 are detachably connected to the carriage-extension 17, the arrangement being such that the web-supply-frame may be quickly removed from the machine. Each leg 32 of the front upright frame member has its lower end curved to partially embrace the front transverse rod 19 of the carriage-extension 17, and is provided with a complementary clamping jaw 36, which may be drawn forcibly toward the leg 32 by turning a knurled headed screw 37, threaded into the leg 32, to cause the jaw to co-operate with the leg to clamp the leg firmly in upright position upon the rod. Each leg 34 of the rear end member has a pin 38 projecting from it, which is received in a clamping plate 39 to correctly locate the latter. A knurled headed screw 40 passes through the clamping plate between the transverse rod 20 and another trans-
verse rod 41 commonly provided at the rear of the carriage-extension 17 for web-guiding purposes, and is threaded into the leg 34 of the rear end member 30. The screw 40 may be turned to draw the clamping plate 39 toward the leg of the end member to clamp the end member securely in upright position. The web-roll-supporting truss 31 consists chiefly of a left web-roll-bearing side member 42 having inturned ends 43 and 44 and a right web-roll-bearing side member 45 having inturned ends 46 and 47. The rear inturned ends 44 and 47 of the side members 42 and 45 co-operate to form the rear end of the truss 31, and the forward inturned ends 43 and 46 co-operate to form the forward end of the truss. The inturned ends of the side members are connected to each other, with provision for widthwise adjustment of the truss to enable the truss to be used with web-rolls of different lengths. A headed screw 48 passes through an elongated slot 49 in the inturned end 44, and is threaded into the inturned end 47, and a similar screw 50 is received in an elongated slot 51 in the inturned end 47, and is threaded into the inturned end 44. One or both of these screws 48 and 50 may be tightened to secure the end members 44 and 47 against relative movement. The forward inturned end members 43 and 46 are similarly connected to each other by screws 52 and 53. Each of the forward inturned ends 43 and 46 is provided with a hook 54 to extend forwardly and downwardly to interfit with one of a series of notches 55 in the horizontal body-portion 33 of the forward frame end member 29, and each of the rear inturned ends 44 and 47 is provided with a similar hook 54 to extend rearwardly and down-

wardly to interfit with one of a series of notches 55 in the body-portion 35 of the rear frame end member 30. A considerable number of these notches 55 is provided, so that various widthwise adjustments of the truss 31 may be accommodated, and so that the truss may be positioned in line with various fields of the platen.

The side members 42 and 45 of the truss 31 have downwardly and rearwardly extending slots 56 in their upper sides, the lower ends of which form bearings for shafts 57 of the work-web-supplying rolls 58. One of these web-supplying rolls 58, as shown in Figure 6, consists of a spool 59 of web, wound on a hollow core 60 which is placed upon a core member 61 mounted on the roll-shaft 57. Arms 62 extend downwardly from the side members 42 and 45 between the ends thereof, and have downwardly and rearwardly directed slots 63, which receive and form bearings for the ends of a web-guiding roll 64. Similar arms 65 extend downwardly from the side members 42 and 45 adjacent their rear ends, and have downwardly and forwardly directed slots 66, which receive and form bearings for a web-guiding roll 67. The work-webs A are unwound from the rolls 58 by rotation thereof in a counterclockwise direction, and are led to the rear over the guide-roll 64, thence around the guide-roll 67 and forward through the carbon-carrier 26 to the platen 11.

The carbon-carrier 26 reciprocates toward and from the platen in the usual manner, but embodies in its construction several features of novelty. The usual carbon-carrying blades are not used although the usual provision is made for their attachment, but instead there are attached to the carbon-carrier two co-operating carbon-roll-supporting brackets 68. Each bracket 68 comprises a transversely-extending portion 69 by which it is attached to the carbon-carrier frame 70, a rearwardly-extending portion 71 for bearing the carbon-rolls 72, and an inturned web-guiding finger 73 for holding the uppermost work-web A down to the carbon-carrier. The transversely-extending portions 69 of the brackets 68 have elongated slots 74 therein, and through each of these slots there passes a screw 75 that is threaded into the rear of the carbon-carrier frame 70 for securing the bracket thereto. The brackets 68 may be adjusted toward and from each other by reason of the screw-and-slot mounting to vary the distance between the bearing portions 71 of the brackets to provide for carbons of different widths corresponding to the different widths of work-webs used. The rearwardly-extending bearing portions 71 of the brackets 68 have open-ended slots 76 which form bear-

ings at their lower ends for carbon-roll shafts 77. Each carbon-roll shaft 77 has a flange 78 at one end, against which one end 79 of a carbon-paper spool 72 wound on a hollow core 80 is placed.

A washer 81 is located on the opposite end of the shaft between the end 79 of the carbon-paper spool and the bracket 68, and upon the threaded outer end of the shaft 10 beyond the bracket there is mounted a knurled headed nut 82. Tightening of the nut 82 draws the shaft 77 lengthwise, causing the flange 78 to bear against the end 79 of the carbon-paper spool and force the 15 other end of carbon-spool 72 against the washer 81. This pressure secures the carbon-spool 72 against rotation relatively to the washer 81, and the pressure of the washer against the bracket 68 prevents rotation 20 of the washer, so that the carbon cannot be unrolled when the nut 82 is turned up tight. The rearwardly-extending portions 71 of the brackets 68 are upwardly inclined, so that the carbon-rolls 72 are arranged 25 conveniently to have the work-webs A led forward between them. When a stretch of carbon is used up, the nuts 82 are loosened and the forward ends of the carbons are held stationary while the carbon-carrier 30 is retracted, to unwind a fresh form-length of carbon. The used up stretch of carbon is then severed with a typed work-web section and the nuts 82 are tightened to again secure the carbon against 35 unwinding.

The carbon-carrier frame 70 to which the brackets 68 are attached is detachably mounted on the base 25 in the manner disclosed in the patent to Benjamin P. Fortin, 40 No. 1,237,819, granted August 21, 1917. The carbon-carrier frame 70 with its carbon-rolls 72 and the web-supporting truss 31 with the work-web rolls 58 may be removed from the machine together therefore, without disturbing the interleaved relation of the carbons B and work-webs A, and may be replaced by a web-supporting truss and a carbon-carrier having webs of a different style or width interleaved with carbons of 45 an appropriate width. Unless the work-webs A are quite narrow, the weight of the web-supplying rolls 58 will be considerable, and their inertia is apt to cause the work to slip relatively to the platen 11 at line-spacing and so to cause irregular line-spacing. Provision is made of a clamp 83, therefore, for drawing the work-web A forward with the carbon-carrier 26, preparatory to typing, to create a slack in the work-web at the rear 55 of the carbon-carrier, so that the rotation of the web-rolls 58 at line-spacing will be unnecessary. This clamp may be like the one disclosed in the patent to Smith, No. 1,364,819, granted January 4, 1921. It comprises a stationary lower jaw 84 on the car-

bon-carrier frame 70 to underlie the work-webs A and carbons B and a swinging upper jaw 85 extending above the work-webs and carbons and pivoted at 86 on the carbon-carrier frame 70. A spring 87 normally draws the swinging jaw 85 down to effective position, and a bell-crank 88, pivoted on the carbon-carrier handle 89, may be moved by a clamp handle 90 slidably mounted on the carbon-carrier handle 89 to 70 render the swinging jaw 85 ineffective. The drawing forward of the carbon-carrier 26, while the clamp 83 is effective, draws the web A from the web-rolls 58 around the guide-roll 67. As the carbon-carrier 26 again moves to the rear, a slack is formed between the guide-roll 67 and the carbon-carrier, which is drawn upon at the subsequent line-feeding of the work. This slack is not permitted to fall at random where it 80 may catch upon stationary parts of the machine or other objects, as it travels from side to side with the carriage, but is supported upon the movable carriage-extension 85 17, the longitudinal rods 21 of the carriage-extension forming a table or frame for supporting the slack.

Variations may be resorted to within the scope of the invention, and portions of the improvements may be used without others. 95

Having thus described my invention, I claim:

1. In a continuous billing typewriting machine, a traveling carriage, a revoluble platen journaled therein, a rear carriage extension, a carbon-carrier on the carriage extension movable with the carriage and also reciprocable toward and from the platen, a plurality of work-web-supplying rolls mounted on the carriage extension above the carbon-carrier and over said carriage extension, means for guiding the work-webs from the web rolls to the rear beyond the rear limit of the carbon-carrier's travel, a clamp on the carbon-carrier for drawing the work-webs from the rolls to create a slack between the rear guiding means and the carbon-carrier to prevent interference with the line-feeding of the work due to the inertia of the web-supplying rolls, and means on the carriage extension to prevent the fouling of the web slack thus created. 100

2. In a continuous billing typewriting machine, a traveling carriage, a revoluble platen therein, a rear carriage extension, a carbon-carrier reciprocable on the carriage extension toward and from the platen, a rail for supporting the rear end of the carriage extension, and a work-web-supply frame mounted on the carriage extension for traveling therewith, the supply frame being so constructed and arranged that the center of gravity of the frame and the work-web carried thereby is located to the front of the rear extension-supporting rail. 110 120 125 130

3. In a continuous billing typewriting machine, a traveling carriage, a revolute platen therein, a carbon-carrier reciprocable toward and from the platen, work-web-supplying means mounted for movement with the carriage, means for withdrawing the work-web from the supplying means to create a slack at the rear of the carbon-carrier to be drawn upon at line-spacing, and means movable with the carriage, arranged to form a guard for the slack to prevent the fouling of the slack as it travels from side to side of the machine. 10
4. In a continuous billing typewriting machine, a traveling carriage, a revolute platen therein, a carbon-carrier reciprocable toward and from the platen, work-web-supplying means mounted above the path of the carbon-carrier for movement with the carriage, and means for guiding the web from said supplying means to the rear of the carbon-carrier, constructed to maintain the web clear of the carbon-carrier. 20
5. In a continuous billing typewriting machine, a traveling carriage, a revolute platen therein, a carbon-carrier reciprocable toward and from the platen, work-web-supplying means mounted above the carbon-carrier for movement with the carriage, web-guiding means to the rear of the carbon-carrier's path around which an upper reach of work-web is led from the web-supplying means and from which a lower reach of the work-web is led forward to and through the carbon-carrier, means for supporting the upper reach of the work-web clear of the carbon-carrier's path, and means for holding the lower reach of the work-web down to the carbon-carrier. 30
6. In a continuous billing typewriting machine, a traveling carriage, a revolute platen journaled therein, a rear carriage extension movable with the carriage, a carbon-carrier reciprocable on the carriage extension toward and from the platen, web-supplying means mounted on the carriage extension comprising web-roll-bearing members extending longitudinally of the machine, and a plurality of web-rolls extending transversely of the machine and arranged to be unwound from the lower side so that none of the rolls will be hidden from the operator at the machine by the unwinding web of another roll, and means for supporting the webs in their passage from the rolls to a position behind the carbon-carrier. 40
7. A carbon-carrier for typewriting machines, comprising a frame, roll-bearing brackets mounted on the frame to support the opposite ends of carbon-rolls, each bracket comprising a laterally-extending portion having an elongated slot therein and a rearwardly-extending bearing portion for the carbon-rolls, and screws received in the slots of the brackets and threaded into the carbon-carrier frame for securing the brackets in various adjusted positions. 50
8. In a continuous billing typewriting machine, a traveling carriage, a platen therein, a carbon-carrier reciprocable toward and from the platen comprising carbon-bearing rolls, each having a supply of carbon wound upon it, and means for guiding work-webs from above the carbon-carrier down beneath the carbon-bearing rolls, the carbon-carrier also comprising means releasable by the operator to permit the removal of the rolls, but normally effective to positively secure the carbon-bearing rolls against upward displacement. 60
9. A carbon-carrier for continuous billing typewriting machines, comprising carbon-bearing rolls, each having a reserve supply of carbon wound upon it and an active stretch of carbon extending forward from it, bearings for the rolls, each roll comprising a shaft and a flange on the shaft to press against one end of the carbon, and means on each shaft operable to move it endwise to cause the flange to press the carbon against one of the bearings to secure the carbon against unwinding. 70
10. In a continuous billing typewriting machine, a traveling carriage, a revolute platen journaled therein, a carbon-carrier reciprocable toward and from the platen, the carbon-carrier comprising a frame, carbon-roll-bearing members mounted on the frame to hold carbons interleaved with separate continuous work-webs, means detachably securing the bearing members to the carbon-carrier frame, and means on the frame arranged to receive carbon-holding blades, the arrangement being such that the carbon-carrier can be quickly converted for use with fan-fold webs by the removal of the roll-bearing members and the attachment of the carbon-holding blades. 80
11. In a continuous billing typewriting machine, a traveling carriage, a revolute platen therein, a carriage extension, a carbon-carrier base reciprocable toward and from the platen, a carbon-carrier detachably mounted on the base, and work-web-supplying means mounted on the carriage extension for movement therewith comprising a truss and supports for the truss, the truss being removable from its supports at the will of the operator to permit the substitution of web-bearing truss and another carbon-carrier having work-webs and carbons. 90
12. In a continuous billing typewriting machine, a traveling carriage, a displaceable platen therein, a carriage extension, a carbon-carrier base reciprocable toward and from the platen, a carbon-carrier detachably mounted on the base, and work-web-supplying means mounted on the carriage extension for movement therewith comprising 100
13. In a continuous billing typewriting machine, a traveling carriage, a platen therein, a carbon-carrier reciprocable toward and from the platen, a carbon-carrier base reciprocable toward and from the platen, a carbon-carrier detachably mounted on the base, and work-web-supplying means mounted on the carriage extension for movement therewith comprising 110
14. In a continuous billing typewriting machine, a traveling carriage, a platen therein, a carbon-carrier reciprocable toward and from the platen, a carbon-carrier base reciprocable toward and from the platen, a carbon-carrier detachably mounted on the base, and work-web-supplying means mounted on the carriage extension for movement therewith comprising 120
15. In a continuous billing typewriting machine, a traveling carriage, a platen therein, a carbon-carrier reciprocable toward and from the platen, a carbon-carrier base reciprocable toward and from the platen, a carbon-carrier detachably mounted on the base, and work-web-supplying means mounted on the carriage extension for movement therewith comprising 130

- 65
- ing a truss, supports for the truss, and web-guiding rolls mounted on the truss for directing the work-webs to the rear of the carbon-carrier, the truss being removable 5 from its supports with its work-webs and guide rolls, and the carbon-carrier with its carbons removable together with the work-webs and carbons interleaved.
13. In a typewriting machine having a 10 traveling carriage, a platen therein, and a carbon-carrier truck, a work-web supply frame mounted upon said carbon-carrier truck for movement with the carriage consisting of roll-bearing members adjustable 15 toward and from each other to accommodate different lengths of web-carrying rolls, and supports for the roll-bearing members having means to mechanically position the roll-bearing members.
14. A work-web supply frame for typewriting machines, comprising a rigid web-roll-bearing truss and supports therefor, the truss consisting of side members to form bearings for the work-web rolls, means connecting the side members to each other and adjustable to vary the space between them to accommodate different widths of work-webs, and hooks on the truss to engage the truss supports, the supports having notches 30 to receive the hooks and thereby mechanically position the truss.
15. A work-web-supply frame for typewriting machines, comprising upright end members, a web-roll-bearing truss consisting of right and left side members, in-turned front and rear ends on both of the side members, means slidingly connecting the in-turned ends of the side members to each other, and means to secure them in adjusted positions.
16. In a continuous billing typewriting machine, a traveling carriage, a revoluble platen journaled therein, a carriage extension mounted for movement with the carriage, work-web-supplying means mounted on the carriage extension comprising web-roll-bearing members adjustable toward and from each other to accommodate web-rolls of different lengths according to the width 50 of work-web required for use, and a carbon-carrier reciprocable toward and from the platen comprising carbon-roll-bearing members adjustable to different distances from each other to accommodate carbon-rolls of different lengths, so that the carbons may be caused to correspond in width to the width of the work-web.
17. A work-web-supplying frame for typewriting machines, comprising long web-bearing members for supporting the opposite ends of several web-rolls, means connecting the bearing members to each other with provision for relative adjustment to vary the space between them to enable them 60 to support web-rolls of different lengths, so that different widths of work-web may be used, and arms secured on the bearing members to form guide-roll bearings for the web, the arms being fast on the web-roll-bearing members and therefore adjustable with them to different positions from each other to accommodate guide-rolls of different lengths in accordance with the width of the work-web.
18. A web-supply frame for typewriting machines, comprising a rigid web-roll-bearing truss and supports therefor, the truss consisting of side members to extend longitudinally of the machine to form bearings for the work-web rolls, and projections on the truss for engaging the supports, the supports having a plurality of notches to receive said projections to determine various adjusted positions of the truss transversely of the machine.
19. A web-supplying attachment for a continuous billing typewriting machine having a traveling carriage, a revoluble platen journaled therein, a carriage extension movable with the carriage, and a carbon-carrier reciprocable toward and from the platen; front and rear end members on the carriage extension, web-roll-supporting means mounted on the end members, and means for detachably securing the front and rear end members to the carriage extension at the front and rear thereof, respectively.
20. A web-supplying attachment for a continuous billing typewriting machine having a traveling carriage, a revoluble platen journaled therein, a carriage extension movable with the carriage comprising a front transverse bar and a plurality of rear transverse bars located vertically one above the other, and a carbon-carrier reciprocable toward and from the platen; front and rear upright end members on the carriage extension, web-supporting means mounted on the end members and rigidly connecting them, and means for detachably clamping the rear upright end member to the two rear transverse bars, the rear transverse bars serving to determine a vertical position of the rear upright end member, and the rear upright end member with the web-supporting means connecting it to the front upright end member serving to determine a vertical position for the front upright end member, and means for detachably clamping the front upright end member to the front transverse bar of the carriage extension.
21. In a typewriting machine, the combination of a traveling carriage, a carbon-carrier mounted to travel with said carriage, said carbon-carrier being shiftable to shift a carbon-sheet to a fresh portion of a work-sheet, and a work-sheet supply roll mounted 115 120 125

to travel with said carriage, said carbon-carrier being effective to unroll the work-sheet from said supply roll.

22. In a typewriting machine, the combination of a traveling carriage, a rear-wardly-extending table to travel with said carriage, a carbon-carrier mounted on said table to travel therewith, said carbon-carrier being shiftable on said table to shift a

carbon-sheet to a fresh portion of a work-sheet, a work-sheet supply roll mounted on said table to travel therewith, and a clamp on said carbon-carrier to grip the work-sheet so that it may be unrolled from the supply roll by a forward movement of the carbon-carrier on said table. 10 15

MAX R. URBAN.
